Patented Apr. 9, 1918.

UNITED STATES PATENT OFFICE.

PAUL KOSACK, OF GRAND ISLAND, NEBRASKA.

WALL CONSTRUCTION.

1,262,212.

Specification of Letters Patent. Patented Apr. 9, 1918.

Application filed July 24, 1916. Serial No. 111,065.

To all whom it may concern:

Be it known that I, PAUL KOSACK, a citizen of the United States, residing at Grand Island, in the county of Hall and State of Nebraska, have invented certain new and useful Improvements in Wall Construction, of which the following is a specification.

This invention relates to an improvement in wall construction for buildings, and has for its principal object to provide such a construction that rectangular wall blocks having greater attenuation than the ordinary ones, may be used for the several courses, the blocks of the courses to be secured transversely of the wall at uniform distances from each other, and the courses to be maintained in vertical alinement until the space between the courses has been filled with cement or other similar adhesive material to form a wall of unusual solidity. The invention includes the use of wall ties constructed of wire so that manufacture will be economical, and the use of T-bars adapted to be disposed vertically between the connected wires of the wall ties in a manner to maintain the blocks of the courses in vertical alinement. The invention also has reference to the formation of recesses in the wall blocks so that the wall ties will not be visible.

With the foregoing objects in view the invention presents a novel construction, combination and arrangement of parts as described herein and claimed, and as illustrated in the accompanying drawing, wherein,—

Figure 1 is a plan view, broken away and showing a wall constructed in accordance with the invention. Fig. 2 is a broken away view on an enlarged scale, being a transverse section on line 2 2 of Fig. 1, a body of cement being added and shown in section. Fig. 3 is an end view of one of the wall ties. Figs. 4 and 5, respectively, are broken away side views of T-bars.

Referring now to the drawing, numerals 6 indicate the outer blocks of a wall, each being formed, preferably, with an ornamental face *a*, the blocks for the inner side 50 of the wall being indicated at 7, and each wall block is provided, to open upon its respective upper and lower side with recesses 8 and 8'. At 9 are indicated wall ties, each being constructed of a pair of wire strands 55 of substantially the same length, each being bent to form a spiral part *a'*, midway be-

tween its ends, and curved adjacent to the spiral part to provide an outwardly divergent part *b* and a pair of outwardly projecting parallel arms *c* and *c'* with opposed transverse terminal loops or hooks *d* and *d'*, and to provide for each arm *c'* a terminal transverse holder-arm *e*, said strands being disposed with the spiral parts *a'* in engagement or in intertwined relation and thereby providing a pair of inwardly convergent recesses 10 between their arms *c* and outwardly divergent parts *b*.

When the blocks 6 and 7 are laid to form wall courses, the wall ties 9 are disposed on the upper side of the blocks, the loops or hooks *d* engaging in the recesses 8 of said blocks, the arms *e* engaging the inner sides of the blocks, said arms operating to maintain the blocks 6 and 7 of a course at uniform distances apart. After the wall ties 9 have been placed in the position indicated the T-bars are inserted vertically in recesses 10 in engagement with the inner sides of said blocks, their function being to maintain the courses in vertical alinement. Cement 12 or similar adhesive material in plastic or semi-plastic form is then deposited between the courses. It soon becomes hardened and the wall thus formed will provide unusual solidity. At the time of laying the courses the hooks or loops *d'* will engage in recesses 8' of the blocks 6 and 7.

As described, the function to be discharged by the hooks or loops *d* and *d'* in conjunction with the respective recesses 8 and 8' is to prevent any outward movement of the blocks of a course and on account of the construction the walls may have such thickness as may be desired without changing the thickness of the blocks, the wall ties 9 being changed in size and proportion to correspond to such requirements, the important feature in this respect being that the holders *e* will bear upon the inner sides 95 of the blocks.

Any suitable arrangement may be made of wire strands for a corner wall tie 13, the parts shown in Fig. 1 for this purpose being the strands 14, 15 and 16, these being 105 bent spirally and assembled to provide terminal loops or hooks for engaging in recesses 17 of the blocks and to provide holder arms 18 for bearings upon the inner sides of the blocks, and to provide recesses 10' 110 within which the T-bars 11' may be vertically disposed, the function to be discharged

by these parts being substantially the same as already described.

Among some of the advantages to be derived by use of the invention, it may be stated that the wire hooks or loops are not visible from the outside of the wall since they are anchored in the recesses of the wall blocks. The wall ties, since they consist of wire strands, may be very economically manufactured, and the T-bars on account of their shape resist stresses to advantage and since they are of metallic construction they will not be injured by contact with the cement which is deposited between the blocks of the courses.

Having fully described my invention what I claim and desire to secure by Letters Patent is,—

In wall construction, the combination of 20 rectangular wall blocks disposed in courses, each block being provided with recesses between its outer and inner faces to open on its upper and lower sides, a plurality of wall ties, each consisting of a pair of 25 metallic strands, each strand being bent to provide a spiral part midway between its

ends, divergent parts outwardly of the spiral part, a pair of adjacent parallel arms with transversely disposed terminals outwardly of the divergent parts and a pair of 30 holder-arms, disposed inwardly of the loops at right angles to said parallel arms, said metallic strands having their spiral parts disposed in intertwined relation with their divergent parts and parallel arms adjacent to each other to provide a pair of recesses, said wall ties being adapted to be disposed between the wall blocks of a lower and upper course with the transversely disposed terminals of said parallel 40 arms disposed in the recesses of said blocks, their holder-arms engaging the inner sides of the wall blocks, and a plurality of T-bars, each being disposed vertically in the recesses of said wall ties in engagement with the 45 wall blocks of an upper and lower course.

In testimony whereof, I have affixed my signature in presence of two witnesses.

PAUL KOSACK.
